Nelson M. Howard

UNITED STATES PATENT OFFICE.

RALPH S. MEGATHLIN, OF QUINCY, MASSACHUSETTS, ASSIGNOR TO UNITED SHOE MACHINERY CORPORATION, OF PATERSON, NEW JERSEY, A CORPORATION OF NEW JERSEY.

MACHINE FOR PREPARING HEEL BLANKS.

Original application filed May 5, 1922, Serial No. 558,684. Divided and this application filed March 9, 1925. Serial No. 14,294.

This invention relates to the preparation of heel blanks, and is illustrated as utilized in fitting low blanks for rubber heel bases by gouging out the seat surface of each blank and deepening the gouge at the breast end to form a scallop which is known in the art as a "blended Coburn lip".

Until recently it has been necessary, in the preparation of heel blanks which were to have a gouge and a "Coburn lip" on their seat surfaces, to perform the gouging and the lip cutting by two separate operations. It has recently been suggested that the two operations could be performed in a single machine, shown as comprising a cutter and a turret carrying a plurality of heel holders, each controlled by a cam to force a heel blank therein toward the cutter near the end of the gouging cut to deepen the gouge to form a scallop fitting over the shank part of the shoe, forming the desired "blended lip" or "blended Coburn lip". Such a machine is shown in United States Reissue Patent No. 15,448, granted Sept. 5, 1922, upon an application filed in the name of Pope.

An object of the present invention is to provide a machine of different type for performing the two operations, which will be especially well adapted for preparing certain kinds of heel blanks such as the low rubber heel bases now used for most men's shoes and for many women's shoes. In the illustrated machine, the blanks are fed to a stationary knife by two rolls one of which is a roll having a matrix or cavity shaped to distort the blank in such manner as to cause the knife to gouge the heel-seat surface of the blank and to deepen the gouge at the breast end of the blank to form a scallop or so-called "blended lip".

A further object of the invention is to provide a machine for gouging and lip-cutting heel blanks as described, which has automatic means for feeding the heel blanks successively to the cutting means, as for example from a magazine. As shown in the drawings, a stationary table may be provided to support each heel blank in turn, and a pusher arranged to reciprocate across the top of the table to advance the heel blanks successively to the gouging and lip-cutting means.

Other objects of the invention, and various novel combinations and improved parts, will be apparent from the following description of the invention as illustrated by the accompanying drawings in which,

Fig. 1 is a cross-section longitudinally of a machine in which the present invention is embodied;

Fig. 2 is a side elevation of the work-engaging parts of the co-operating rolls;

Fig. 3 is a section, partly broken away, through the rolls, on an enlarged scale;

Figs. 4, 5 and 6 are views showing the successive steps of preparing a heel blank according to a novel method; and

Fig. 7 is a longitudinal section of a heel blank after it has been operated upon by the machine.

As shown in Fig. 1, the general organization of the machine comprises co-operating heel blank feeding and distorting rolls 10 and 12, a stationary knife 14 to skive the waste material from heel blanks distorted thereby, and mechanism automatically to present heel blanks successively thereto. The heel blanks are stacked on a stationary table 16 in a magazine 18, under a presser 20, and are advanced successively to the rolls by a pusher 22 reciprocating over the table. Parts not hereinafter fully described may be, and are shown as being, the same as those described in United States Letters Patent No. 961,736, granted June 14, 1910, on application of J. R. Scott, and No. 1,300,-627, granted April 15, 1919, on application of E. E. Lane.

As shown in Fig. 2, roll 10 comprises a plurality of sections formed with teeth which sink into the waste portion of the work to a greater or less extent. To distort the blanks against the teeth of roll 10, roll 12 is formed with a cavity 24 deep enough along its front and sides to protect the sides and rear end of a heel blank, as shown at 26. An intermediate portion 28, extending from B to C, in Fig. 3, which grades into the deep portion 26 from A to B, is of an intermediate depth, and is substantially concentric of the roll, to form the flat bottom 56 of the gouge in each heel blank (Fig. 7). The intermediate portion 28 grades into a shallow portion 32, extending from C to D, which forms the lip 58.

By comparing Figs. 2, 3, 6 and 7, it will be seen that roll 12 is formed with a sharp rise at the beginning of the portion A—B, firmly to grip the blank and carry its forward edge under knife 14, then a portion A—B of gradually increasing radius to form the bevel 54, then a concentric portion 28 extending from B to C to form the bottom 56 of the gouge, and finally a portion 32 extending from C to D to form the lip 58. The portion 26 is made somewhat larger than the usual blanks to permit use of the roll on larger blanks if desired. Although when so used the size of gouge and lip is the same as on the smaller blanks, it is often desirable thus to vary the size of the blanks without changing the treatment of them.

When the machine is used in gouging and scalloping hard heel blanks of substantially uniform thickness throughout, it is desirable to provide comparatively long, slender teeth on the roll 10 so that the teeth may sink well into the blank and thus avoid putting an undue strain upon the bearings of the two rolls. In order, however, to permit the use of shorter, thicker teeth, which are stronger and hence more desirable, the heel blanks, which commonly comprise a plurality of heel lifts, may be prepared by assembling one or more whole lifts 50 with a lift having a cut-away middle portion such as the horseshoe-shaped lift 52. As shown in Fig. 2, this assembly is sufficiently near the desired final shape that the short, strong teeth may be employed on roll 10 without any undue pressure tending to wedge rolls 10 and 12 apart.

In carrying out my invention, a number of heel blanks are stacked in the magazine 18 under the presser 20. Thereafter pusher 22 advances the heel blanks successively to rolls 10 and 12, which co-operate with knife 14 to form on each heel blank a gouge 56 and an adjoining blended lip 58.

The method of assembling a heel blank of a plurality of lifts one of which has a cut-away middle portion and then gouging and scalloping the blank is not herein claimed but forms the subject-matter of application Ser. No. 558,684, filed May 5, 1922, of which the present application is a division.

Having described my invention, what I claim as new and desire to secure by Letters Patent of the United States is:—

1. A machine of the class described having, in combination, a knife and a pair of rolls for feeding a blank to the knife, one of said rolls having teeth adapted to penetrate the blank and the other roll having a cavity shaped to bend the middle portion of the blank past the plane of the cut of the knife sufficiently to cause a gouge to

be formed in the blank and to bend a succeeding portion of the blank progressively still further past the plane of the cut to cause a blended scallop to be formed at the breast end of the blank. 65

2. A machine of the class described having, in combination, a knife and a pair of rolls for feeding a blank to the knife, one of said rolls having teeth adapted to penetrate the blank and the other roll having a cavity, said cavity having depth enough around its leading end and sides to receive substantially the full thickness of the blank, having a shallow middle portion to bend the middle portion of the blank above the periphery of the roll and having a following portion 70 which is progressively shallower than the middle portion to bend the corresponding portion of the blank still farther above the periphery of the roll. 75

3. A machine of the class described having, in combination, a knife and a pair of rolls the axes of which are held from movement away from each other for feeding a blank to the knife, one of said rolls having teeth adapted to penetrate the blank and the other roll having a cavity shaped to bend the middle portion of the blank past the plane of the cut of the knife sufficiently to cause a gouge to be formed in the blank and to bend a succeeding portion of the blank progressively still further past the plane of the cut to cause a blended scallop to be formed at the breast end of the blank. 85 90 95

4. A machine of the class described having, in combination, a magazine for a stack of heel blanks, means for delivering blanks one by one from the stack, a presser roll and a co-operating cavity roll to receive between them each blank as it is delivered from the stack, the cavity being so shaped that the blank is distorted first to raise part of the middle portion of the blank above the periphery of the cavity roll and then to raise a following portion of the blank still farther above said periphery, and a stationary knife adapted to operate upon the blank while the blank is distorted to cut in it a gouge and a blended scallop. 100 105 110

5. A cavity roll for a machine of the class described having formed therein a cavity comprising a deep horseshoe-shaped portion 115 120 125 to receive the side and rear portions of a heel blank, and a portion of less depth between the arms of the horseshoe to distort the blank for gouging and lip-cutting, the horseshoe-shaped portion being of somewhat larger outline than is the outline of a given blank so as to permit use of the roll not only with blanks of the given outline but with blanks of a larger outline.

In testimony whereof I have signed my name to this specification.

RALPH S. MEGATHLIN.
